(57) **CLAIM**

The ornamental design for a hula hoop, as shown and described.

DESCRIPTION

1. Hula hoop

1.1 : Perspective

1.2 : Front

1.3 : Back

1.4 : Left

1.5 : Right

1.6 : Top

1.7 : Bottom

The product (hula hoop) is made of a synthetic resin, a rubber and a metal; the product is an exercising tool that is twirled around a part of a body, for example, a waist or neck; a sensor for detecting the motion of this product is installed in the interior of this product; and a power button for operating the sensor and a display part for displaying the sensor's signal are installed at a surface of this product; the creative part of this design is the shape and form of the hula hoop.
